UNITED STATES PATENT OFFICE.

GARRETT B. CUBBERLEY, OF MILWAUKEE, WISCONSIN.

IMPROVEMENT IN BLACKSMITHS' HAMMERS.

Specification forming part of Letters Patent No. 136,139, dated February 25, 1873.

To all whom it may concern:

Be it known that I, GARRETT B. CUBBERLEY, of Milwaukee, in the county of Milwaukee and the State of Wisconsin, have invented certain Improvements in Blacksmiths' Strikers, of which the following is a specification:

Nature and Object of the Invention.

My invention consists in improvements in a striker to be managed by the foot or hand, and to be operated by the blacksmith, and do the work of another man, and can be shifted forward or back so as to strike on any part of the anvil, striking a hard or a light blow at the will of the operator.

Description of the Drawing forming part of the Specification.

Figure 1 is a perspective view of my invention, and Fig. 2 a plan view.

General Description.

A is the frame; B, the hammer; C C, pulleys on the hammer-shaft; D D, straps attached and around pulleys C C; E, an elliptic spring to raise the hammer after the blow has been struck; G G, rods connected with the ends of spring E and connection M; H, lever by which the machine is operated; I, connecting-rod from the end of lever H to treadle U; K, lever attached to the machine to move it back and forth in front of the anvil; L L, trucks on which the machine runs on a track; M, screw-connection by which the rods

G are connected to one of the straps D to raise the hammer; N, connection joining lever F to one of the straps D on pulley C to bring the hammer down; O, fastening of lever F to frame A; P, fastening of spring E to frame A; Q, roller on which lever H works; R, shaft to which the handle of the hammer is attached; S, hammer-handle; T, spring attached to frame A and lever F to bring lever F back again; U, treadle with which the machine is operated.

Operation.

Put your foot on treadle U and press down, and hammer B will strike on the anvil, since connection N will be thrown up, causing the shaft R to roll. When the foot is raised the spring E will cause the shaft to roll in the opposite direction, and thus raise the hammer again.

Claims.

I claim as my invention—

1. Hammer B, pulleys C, shaft R, handle S, spring E, connecting-rods G G, straps D, and connection M, in combination with levers F and H, connecting-rod I, and frame A, substantially as described.

2. Rollers L and handle K, substantially as described, in combination with the above.

GARRETT B. CUBBERLEY.
